UNITED STATES PATENT OFFICE.

SAMUEL E. FLINT, OF ST. LOUIS, MISSOURI, ASSIGNOR OF ONE-THIRD TO
WILLIAM F. MILLS, OF SAME PLACE.

SMOKE-PREVENTER FOR FURNACES.

SPECIFICATION forming part of Letters Patent No. 406,393, dated July 2, 1889.

Application filed April 16, 1889. Serial No. 307,478. (No model.)

To all whom it may concern:

Be it known that I, SAMUEL E. FLINT, a citizen of the United States, residing at the city of St. Louis, State of Missouri, have invented 5 a certain new and useful Improvement in Smoke-Preventers for Steam-Boiler and other Furnaces, of which the following is a full, clear, and exact description.

My invention relates to improved means of 10 preventing smoke in steam-boiler and other furnaces, and is an improvement on that for which Letters Patent of the United States were granted to me, dated November 6, 1888, No. 392,549, for improvements in smoke-pre- 15 venters for steam-boiler and other furnaces, wherein the principal feature consists in the combination, with a fire-chamber, of an injector-jet (or series thereof) having a perforated nozzle-cap which incloses the jet and 20 forms a mixing-chamber, and of an outer air-tube inclosing the jet and its cap, whereby a mixture of air and steam is directed into the fire-chamber and effects a combustion of the 25 gases and smoke evolved from the burning fuel before they pass into the flues and chimney.

My present invention consists in additional features of novelty, as hereinafter claimed.

On the accompanying drawings, Figure 1 30 represents a front elevation of a steam-boiler furnace with my invention applied thereto; Fig. 2, a longitudinal section thereof broken away; Fig. 3, a transverse section on line 1 1 in Fig. 2, omitting the fire-bars; Fig. 4, a longitudinal sectional view, to an enlarged scale, 35 of one of the nozzles or injectors and its appurtenances forming the essential part of my invention, as seen to the left of Fig. 2; Figs. 5 and 6, outer and inner end views thereof, re- 40 spectively; Fig. 7, a transverse section on line 2 2 in Fig. 4; and Fig. 8, a detached longitudinal section, to an enlarged scale, through the nozzle on line 3 3 in Fig. 4; Fig. 9, a de- 45 tached front view, to an enlarged scale, of two adjacent fire-bridge air-pipes, forming part 50 of my invention, as seen in Fig. 3; and Fig. 10, a side sectional view thereof, taken on line 4 4 in Fig. 9, or as seen to the right of Fig. 2; Fig. 11, a longitudinal section through 55 one of the nozzles and its combined parts as

applied to a fire-chamber having a double shell and intervening water-space, and Fig. 12 an outer end view thereof.

Like letters of reference denote like parts in all the figures.

Referring to Figs. 1 to 8, A represents a steam-boiler, broken away longitudinally, having the furnace-chamber B, fire-grate C, bridge D, and ash-pit E. In and across the front of the furnace-chamber B are arranged, 60 at suitable distances apart above the grate C, nozzles or injectors, each composed of a pipe a, having a curved or conical reduced end or nozzle a', (see Fig. 8,) around which is screwed or otherwise attached a tubular cap b, having 65 a curved or conical reduced end or nozzle b', which is in advance of and in line with the nozzle a', so as to form a chamber c between the nozzles a' b'. Through the wall of the tubular cap b are perforations d, which admit air from the outside of the tubular cap b to the chamber c. The pipe a with its nozzles a' b' are inclosed within a cylindrical (or other shaped) pipe e, open at one end adjacent to the nozzle b', and formed 70 through its other end adjacent to the front f of the boiler A with openings g for admitting air from the outside of the pipe e to the annular space between the pipes a and e. Surrounding the pipe e is a second pipe h, 80 which is preferably rectangular in cross-section and of a diminishing taper vertically from its open end adjacent to the front f of the boiler A to its inner open end, which projects beyond and is centrally in line with the 85 nozzle b'. Surrounding the pipe h is a third pipe i, open at both ends and similar in shape and arrangement to pipe h, beyond which its inner end projects toward the furnace B. By this arrangement air is admitted from the 90 outside of the front wall of the furnace-chamber B through the adjacent outer ends of the pipes h and i into the spaces between the pipes e h and h i, respectively.

The injectors constructed as above de- 95 scribed are let into vertically-inclined holes formed through the fire-brick lining beneath the front end of the boiler A at a suitable height from the dead-plate j, so that the longitudinal center lines of the injectors may be 100

arranged at varying angles, respectively, to the fire-grate C, as indicated by the arrows in Fig. 2.

The nozzle-pipes *a* of the injectors are connected together outside the furnace B by a horizontal pipe *l*, which communicates with the steam-space of the boiler A by the upright pipe *l*, having a regulating-valve *m*, or in any other desirable manner.

- 10 In the wall of the fire-bridge D, facing the ash-pit E and immediately beneath the bearer *n* of the fire-grate C, are arranged, at suitable distances apart across the ash-pit E, passages or pipes *o*, which extend rearward and upward through the bridge D, and thence forward to the face of the bridge D, where they communicate with the furnace-chamber B at a suitable height from the fire-grate C, the pipes *o* being preferably square or rectangular
- 15 in cross-section, and communicating with each other by spigot and faucet connections *o'*, as seen more particularly in Figs. 9 and 10, by which arrangement warm air from the ash-pit E enters and circulates within the pipes *o*,
- 20 and, passing upward through the bridge D, is thereby further heated, and thence finally issues at a high temperature into the furnace-chamber B, where, mingling with the products of combustion from the fuel on the grate C,
- 25 30 intense heat and active combustion are induced.

In operation, on opening the regulating-valve *m*, steam is admitted through pipes *l* *k* into the injector-pipes *a*, from which it passes, in the form of jets, through the nozzles *a'*, chambers *c*, and nozzles *b'* into the forward-lying portions of the pipes *e*, whereby a partial vacuum is formed in the chambers *c* and within the pipes *e*, which causes warm air to be drawn from the space *q* between the front *f* of the boiler A and the furnace B, through the openings *g* into the pipes *e*, where it circulates around the nozzle-pipes *a* and passes through the perforations *d* of the nozzle-caps *b* into the chambers *c*, whence it is carried off with the passing steam through the nozzles *b'* into the forward-lying portions of the pipes *h*, in which a partial vacuum is thereby formed, and warm air drawn from the space *q* through the pipes *h*, and so on in like manner through the projecting portions of the pipes *i*, from the inner end of which the combined steam and accumulated accessions of warm air finally issue in a more or less compressed and highly oxygenated state into the furnace-chamber B, where, mingling with the draft and products of combustion, an intense heat is thereby generated and thorough combustion of the gases and smoke effected,

55 60 65 the effect being greatly increased by the simultaneous commingling of the warm air entering the furnace B through the pipes *o'* in the fire-bridge D.

If desired, the successive series of pipes surrounding each injector may be increased,

according to the number of injectors used, capacity of furnace-chamber, and volume of air required therefor.

By this invention the indraft of air produced by the exhaustive action of the steam-jet is made co operative with the latter at the mouth of each successive air-duct, so that the volume of air injected into the furnace-chamber is accumulative and correspondingly larger than that which would be injected when the same jet is surrounded by a single pipe of the combined area of the series of pipes *e*, *h*, and *i*.

I do not limit myself to the rectangular and tapered shape of the pipes *h* and *i*, which may be made square, circular, or otherwise and parallel with each other, as may be found best in practice.

In the application of my invention to the fire-box of a locomotive or other furnace having a double shell and intervening water-space the injector-tube *e* is surrounded (as shown in Figs. 11 and 12) by a single cylindrical air-pipe *h'*, which extends beyond the injector-tube *e* and opens at its inner end 90 into the furnace, the pipes *e* and *h'* receiving air through their outer ends from the outside of the boiler.

I claim—

1. In a steam-boiler or other furnace, the combination of an injector-jet having a perforated nozzle-cap, which incloses the jet and forms a mixing-chamber, an air-tube inclosing and extending beyond the jet and its cap, and an outer air-tube surrounding and substantially as shown, and for the purpose described.

2. In a steam-boiler or other furnace, the combination of an injector-jet having a perforated nozzle-cap, which incloses the jet and forms a mixing-chamber, an air-tube inclosing and extending beyond the jet and its cap, and a series of air-tubes placed one within the other around the injector-tube and extending, respectively, beyond the latter and each other, substantially as shown, and for the purpose described.

3. In a steam-boiler or other furnace, the combination of a series of injector-jets having perforated nozzle-caps and surrounding air-tubes, all constructed and arranged substantially as described, with a series of air-tubes communicating with each other and opening from the ash-pit through the fire-bridge into the furnace-chamber, substantially as shown, and for the purpose described.

In testimony whereof I affix my signature in presence of two witnesses, this 6th day of April, 1889.

S. E. FLINT.
